UNITED STATES PATENT OFFICE

110,010

DESIGN FOR A MANICURE IMPLEMENT

Philip F. Accocella, Brooklyn, N. Y.

Application July 14, 1937, Serial No. 70,422

Term of patent 3½ years

To all whom it may concern:

Be it known that I, Philip F. Accocella, a citizen of the United States, residing at 81 Wolcott Street, Brooklyn, Kings County, New York, have invented a new, original, and ornamental Design for a Manicure Implement, of which the following is a specification, reference being had to the accompanying drawing, forming part thereof.

Fig. 1 is a perspective view of a manicure implement showing my new design.

Figs. 2 and 3 are sections taken substantially on the lines 2—2 and 3—3 of Fig. 1, looking in the direction of the arrows.

What I claim is:

The ornamental design for a manicure implement substantially as shown and described.

PHILIP F. ACOCELLA.
